BY Victor J. Evans

ATTORNEY

WITNESS:

Gerald Henney.

UNITED STATES PATENT OFFICE.

JOHN J. KLESCHKA, OF WATERBURY, CONNECTICUT.

FOB.

Application filed April 16, 1926. Serial No. 102,515.

Fraternity, lodge and other society buttons are designed to be arranged in the button hole of a garment, and frequently become entangled with other people's clothing, while 5 members of the society are standing close together, thus inflicting injury to the clothing of both parties. It is, therefore, my aim to provide a watch fob of a construction whereby such buttons may be readily attached 10 thereto and securely sustained thereon so that the fraternal insignia will be fully displayed without liability of inflicting injury to other person's clothing or to his own and likewise wherein the construction is such as to be 15 highly ornamental.

To the attainment of the foregoing, reference is to be had to the drawings which accompany and form part of this application.

In the drawings:

20 Figure 1 is a perspective view of the improvement.

Figure 2 is an approximately central vertical sectional view therethrough.

Referring now to the drawings in detail, 25 the numeral 1 indicates the fob plate and 2 the strap. Either of these elements may be of any ordinary construction, the fob plate being preferably of an ornamental nature and, of course, any required design.

30 The plate, on its rear face is formed with a round depression that provides a pocket 3 and with a central opening 4 that passes through the pocket. If desired the outer face of the fob plate may be also formed with a 35 pocket but in any event the said outer face is notched to one side of the opening, as at 5.

The button proper is indicated by the numeral 6, the same being provided on its inner face with the usual lug 7, which in this instance is designed to be received in the wedge

40 pocket 5. The button 6 on its inner face is also provided with the usual neck extension 8 that has interior threads for engagement with the threaded stud 9 on the inner headed member 10 of the button. The inner headed member 45 is designed to be received in the pocket 3 and to be wholly concealed therein so that the same will not contact with the clothing of the wearer. Obviously the stud carrying member 10 may be easily attached 50 to or removed from the head of the button 6 and the simplicity of my construction and the advantages thereof will be perfectly apparent to those skilled in the art to which such invention relates when the foregoing 55 description has been carefully read in connection with the accompanying drawings.

Having described the invention, I claim:

A fob designed to provide a display holder 60 for an emblematic button, said button comprising separable heads, one having a neck extension interiorly threaded, and a stud projecting from the other head and adapted to be screwed into the neck extension, said fob comprising a flat plate having a recess formed 65 on one side thereof and adapted to receive one head of the button provided with said stud, and with said head wholly lying within the plane of the fob, the other side of said fob plate having a notch formed therein, and 70 also provided with a central opening adjacent said notch and communicating with said recess, said opening receiving the neck extension of the other head of the button, and a lug projecting inwardly from the last mentioned head of the button and adapted to be received by said notch.

75 In testimony whereof I affix my signature.

JOHN J. KLESCHKA.
